UNITED STATES PATENT OFFICE

JORDAN A. GEORGOFF, OF HARBIN, CHINA

CIRCULATING SYSTEM

Application filed May 31, 1930. Serial No. 458,155.

This invention relates to improvements in steam boilers, the general object of the invention being to provide means for increasing the circulation of the water in the boiler and reducing the consumption of fuel by providing a series of tubes in the fire box of the boiler so arranged that water will pass from the lower part of the boiler through the tubes into the upper part of the front portion of the boiler.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:—

Figure 1 is a section on line 1—1 of Figure 2.

Figure 2 is a section on line 2—2 of Figure 1.

Figure 3 is a section on line 3—3 of Figure 2.

Figure 4 is a top plan view of the casing on the top of the fire box and with which the vertically arranged tubes communicate.

In these views, the numeral 1 indicates a diagonally arranged tube having its lower forward end welded to the front wall 2 of the fire box, with the open end of the tube in communication with the lower end of the boiler. The upper end of the tube is closed. A plurality of vertical tubes 3 have their lower ends in communication with the tube 1 and their upper ends pass through the top wall 4 of the fire box. I prefer to connect the upper ends of these tubes with a plate 5 which fills an opening in the top wall of the fire box and is welded or otherwise fastened to said wall.

An elongated casing 6 is formed with or connected to the upper face of the plate 5, this casing having its front end open and its rear end closed so that the casing is in communication with the top part of the

boiler, as shown in Figure 2. Thus this casing forms a channel closed at its rear end and open at its front end into which the vertical tubes 3 discharge. Stay rods 7 connect the top wall of the housing or casing 6 with the top of the boiler, the lower ends of these rods being enlarged and threaded in holes in the top of the casing, as shown at 8.

I prefer to make the tube 1 in two sections 60 which are welded together, as shown at 9, so as to facilitate the welding of the tubes 3 to said tube 1.

A clean-out plug 10 may be placed above each tube 3 in the top of the casing to enable the tubes to be cleaned, though such plugs can be dispensed with as the intense circulation produced by the invention will tend to keep the tubes free of scale.

By connecting the casing 6 with the plate 70 5, the parts of the invention can be assembled and connected together and then the plate placed in the opening in the wall 4 so that the invention can be readily attached to a boiler.

From the foregoing it will be seen that the water from the lower part of the boiler will enter the tube 1 and then pass up through the tubes 3 into the casing 6 and it will then pass from the front end of the casing into the upper part of the boiler. The water in the tubes 1 and 3 will be intensely heated due to the fact that the tubes are located in the fire box directly above the fire. Thus the water will be quickly turned into steam and the steam, together with the water, will pass upwardly through the vertical tubes and into the casing. Attention is called to the fact that the steam and water is prevented from entering the steam space 80 over the top of the fire box as the casing prevents this and causes the steam and water to pass with considerable velocity into the rear part of the boiler, where the casing discharges into the same. Then this water, 85 having given up its steam, will drop downwardly and again pass into the tube 1. As many of these units can be used as desired and according to the size of the boiler, Figure 1 showing two of the units in use.

Thus this invention adds to the heating surface of the fire box and insures an intensive circulation of the water in the boiler, which results in a considerable saving of fuel. It also insures dryness of the steam as the casing prevents particles of water from penetrating into the steam space above the fire box. The formation of steam in the whole boiler will be very regular due to the intense circulation, which in turn, also results in generation of dry steam.

It is thought from the foregoing description that the advantages and novel features of the invention will be readily apparent.

15 It is to be understood that changes may be made in the construction and in the combination and arrangement of the several parts, provided that such changes fall within the scope of the appended claims.

20 What I claim is:—

1. In combination with a locomotive boiler having a fire box, a crown sheet and a throat sheet, a casing having its sides and rear end closed, and its forward end opened and extending longitudinally of said crown sheet above the same and terminating adjacent the forward end thereof, and a thermic siphon comprising a diagonally disposed tubular portion connected at its lower end to said 25 throat sheet, and having a plurality of vertically arranged tubes extending from said tubular portion and arranged to open into said casing.

2. In combination with a locomotive boiler having a fire box with an elongated opening in the top thereof, a plate closing said opening, a throat sheet, a casing having its sides and rear end closed and its forward end open and extending longitudinally of said plate 35 above the same and terminating adjacent the forward end thereof, and a thermic siphon comprising a diagonally disposed tubular portion connected at its lower end to said throat sheet, and having a plurality of vertically arranged tubes extending from said 40 tubular portion and passed through said plate and opening into said casing.

In testimony whereof I affix my signature.
JORDAN A. GEORGOFF.
